CLAIM

The ornamental design for a device for use in protecting freshly polished nails while drying, as shown and described.

DESCRIPTION

FIG. 1 is a front elevational view of the device for use in protecting freshly polished nails while drying showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

The strap portion of the design is shown partially broken away in the various views to indicate indeterminate length.
